DESIGN FOR A HAT OR SIMILAR ARTICLE

Harry Bonn, Union City, N. J.

Application March 16, 1946, Serial No. 127,589

Term of patent 7 years

(CL. D3—13)

To all whom it may concern:

Be it known that I, Harry Bonn, a citizen of the United States of America, residing in Union City, county of Hudson, and State of New Jersey, have invented a new, original, and ornamental Design for a Hat or Similar Article, of which the following is a specification, reference being had to the accompanying drawing, forming part thereof, wherein:

Figure 4 is a plan view showing the hat or similar article in flat position.

I claim:

The ornamental design for a hat or similar article, substantially as shown.

HARRY BONN.
